United States Patent Office

Des. 179,205
Patented Nov. 13, 1956

179,205

SEPARATOR FOR MEAT AND PRODUCE

Nola D. Levie, Los Angeles, Calif., assignor to Ekco Products Company, Chicago, Ill., a corporation of Illinois

Application March 12, 1956, Serial No. 40,556

Term of patent 14 years

(Cl. D11—1)

Fig. 1.

Fig. 2.

Fig. 3.

Fig. 4.

Fig. 1 is a top perspective view of a separator for meat and produce, showing my new design, with a portion of the article broken away to shorten its longitudinal dimension for convenience of illustration.

Fig. 2 is a fragmentary top plan view thereof.

Fig. 3 is an end elevational view thereof.

Fig. 4 is a fragmentary side elevational view thereof.

I claim:

The ornamental design for a separator for meat and produce, as shown.
